UNITED STATES PATENT OFFICE.

JOHN M. OLIN, GEORGE W. SCHAUERTE, AND HANS ERNST, OF EAST ALTON, ILLINOIS,
ASSIGNORS TO WESTERN CARTRIDGE COMPANY, OF EAST ALTON, ILLINOIS, A COR-
PORATION OF DELAWARE.

SIZING MACHINE FOR PAPER SHELLS.

Application filed February 10, 1923. Serial No. 618,241.

To all whom it may concern:

Be it known that we, JOHN M. OLIN, GEORGE W. SCHAUERTE, both citizens of the United States, and HANS ERNST, a subject of the King of Great Britain, all residing at East Alton, county of Madison, Illinois, have invented the new and useful Improvement in Sizing Machines for Paper Shells, of which the following is a specification.

This invention relates to machine for sizing paper tubes or the like.

In the art of making paper tubes, as, for instance, for the manufacture of paper shells such as are used in shot guns and the like, it is often necessary to size the tubes with considerable accuracy so that the shells may accurately fit the bore of the gun. Since the tubes are made of paper and are, therefore, somewhat weak, the sizing process must be carried on without subjecting the tubes to undue strain such as would take place, for instance, if a tube were held at one end and forced through a die beginning at the other end as is usual in sizing other kinds of tubes. Furthermore as it is practically impossible to remove all strain from the tube during the sizing process, provision must be made for stopping the operation in case of failure of the tube by breaking, buckling or the like or choking of the machine or other abnormal condition.

One of the objects of this invention, therefore, is to provide a tube sizing machine wherein the tube shall be held for operation so as to avoid unduly straining the tube.

Another object of this invention is to provide such a machine which shall automatically stop the operation in case of abnormal conditions developing.

Another object of this invention is to provide novel means for greasing the tube before subjecting it to the sizing operation.

Further objects will appear from the detail description taken in connection with the accompanying drawings, in which:

Figure 1 is a front elevation of one end of a machine embodying this invention;

Figure 2 is a front elevation of the other end of the machine;

Figure 3 is an end elevation as seen from the right hand end of Figure 2;

Figure 4 is a horizontal section taken on line 4—4, Figure 1;

Figure 5 is a vertical section on line 5—5, Figure 2;

Figure 6 is a detail showing the arrangements for stopping the operation upon failure of a tube; and

Figure 7 is a section on line 7—7, Figure 6.

Referring to the accompanying drawings, the machine comprises a bed 1 supported on piers 2. Mounted on brackets 3 and 4 on the bed 1 is a tube magazine comprising a pair of up-right channels 5 and 6, closed at the bottom by lips 118 into which the tubes 7 may be inserted either by hand or by suitable automatic machinery not shown. The tubes 7 have their ends confined in the channels 5 and 6 and rest one upon another in a vertical stack. Supported on the brackets 3 and 8 on the bed 1 is a tube greasing device comprising a hopper 9 into which suitable greasing material, such as vaseline, may be fed. The hopper 9 communicates with a horizontal cylindrical barrel 10 traversed by a shaft 11 carrying a screw-conveyor 12. One end of the barrel 10 is provided at the side nearest the tube magazine with a series of perforations 13 adapted to deliver grease to the greasing roll 14. The roll 14 is mounted to rotate with its face in contact with the barrel 10 at the perforations 13, and to contact also with the tubes 7 descending in the channels 5 and 6. As the tubes feed downwardly step by step, along the tube magazine, each one comes in contact with the roll 14 and receives therefrom a partial coating of grease at one end thereof.

The machine is driven by a belt 15 from any suitable source of power not shown. The belt 15 acting through a pulley 16 rotates the shaft 17 connected by a releasable clutch 18 to a shaft 19 which, when the clutch 18 is in engagement, forms an extension of the shaft 17. The shaft 19 carries a bevel pinion 20 engaging a bevel gear 21 on a transverse shaft 22 mounted underneath the bed of the machine.

The shaft 22 also carries a spur pinion 23 meshing with a gear 24 on a crank shaft 25 mounted transversely of the bed. The crank shaft 25 is provided with a crank pin 26 having a bearing in a sliding block 27

which is adapted to slide in guides 28 on a lever 29 pivoted at 30 near the bottom of one of the piers 2. Pivoted at 31 to the upper end of the lever 29 is a link 32 which connects the lever 29 with a sliding block 33. The block 33 is arranged to slide on ways 34 arranged within the bed 1. The block 33 carries a transverse shaft 35 carrying at one end thereof a pinion 36 meshing with a stationary rack 37 fixed to the bed 1, and at the other end a gear 38 meshing with a rack 39 on a sliding carriage 40. The carriage 40 is arranged to slide on ways 41 on the bed 1.

15 The crank shaft 25 carries at its rear end a bevel gear 42 adapted to mesh with a corresponding bevel gear 43 on a shaft 44 running in a direction longitudinally of the bed and mounted in suitable bearings 45. The shaft 44 carries at its extremity a cam 46 engaging a cam roller 47 on an arm 48 pivoted at 49 on the pier 2 and having an extension 50 connected with a spring 51 suitably anchored at 52 on the pier so as to maintain the roller 47 in engagement with the cam 46. Pivoted at 520 at the upper end of the arm 48 is an adjustable link 53 connected with one arm of a bell crank 54 mounted on a pin 55 and carrying at its other end a pawl 56 adapted to engage a ratchet 57 also mounted on the pin 55. A spring 58 connected to the pawl 56 and the bell crank 54 holds the pawl in engagement with the ratchet. Mounted on the pin 55 and fixed to the ratchet 57 is a gear 59 meshing with a pinion 60 on the rear end of a shaft 61 running lengthwise of the bed and having bearings in brackets 62 and 4 thereon. The shaft 61 passes through a bracket 63 depending from the carriage 40, said shaft being splined to a sleeve 64 having a bearing in said bracket and having fixed thereto a pinion 65 engaging a gear 66 on a rotating head 67 mounted for rotation in a housing 68 on the carriage 40.

45 The head 67 carries at diametrically opposite points thereon a pair of mandrels 69 adapted to carry and support a tube during the sizing operation.

50 The operation of the mechanism so far described is as follows: The shaft 19 being uniformly driven and acting through the gears 20, 21, 23 and 24 drives the crank shaft 25 at a uniform rate. The crank shaft 25 acting through the pin 26 and the block 27 working in the guides 28 moves the lever 29 with a reciprocating motion about the pivot 30 so as to move the upper end of the lever 29 forward and backward along the bed 1, the forward movement being comparatively slow and the backward movement more rapid on account of the varying leverage of the pin 26 with respect to the pivot 30. The lever 29 acting through the link 32 moves the block 33 with a corresponding reciprocating movement along the ways 34.

As the block 33 moves forward or to the left, Figure 2, the engagement of the gear 36 with the rack 37 will cause the shaft 35 to rotate, thereby driving the gear 38 and, therefore, the rack 39 so as to move the carriage 40 forward along the ways 41. This movement moves one of the mandrels 69 which has previously received a tube thereon with a feeding movement through the sizing apparatus to be described presently. At the same time the other mandrel 69 will be passed into the lowermost tube in the magazine channels 5 and 6. Upon return movement of the arm 29, the carriage will again be drawn back so as to withdraw the mandrels 69, the first one leaving its tube in the sizing apparatus as will presently be described, and the other carrying with it the lowermost tube from the tube magazine, the web of the channel 6 being cut away at the lowest point to permit such withdrawal.

70 The shaft 44 carrying the cam 46 rotates at the same speed as the crank shaft 25, the gears 42 and 43 being equal. Consequently the arm 48 which is actuated by the cam 46 will be reciprocated once for each movement of the carriage 40 forward and back. The cam 46 rotates in the direction indicated by the arrow in Figure 3. It will be noted that this cam is provided with a sudden rise at 70. The cam is adjusted so that this sudden rise engages the roller 47 just as soon as the carriage 40 has been withdrawn until the mandrels 69 are clear of the sizing mechanism and the tube magazine. When this engagement takes place, the arm 48 will be quickly moved to the left, Figure 3, whereby the bell crank 54 will be given a corresponding movement so as to turn the ratchet 57 through a distance corresponding to the throw of the pawl 56 in the present case one-third of a revolution. This has the effect of turning the gear 59 through part of a revolution. This gear in turn rotates the pinion 60 and the shaft 61 carrying the gear 65 which in turn rotates the gear 66. The gear ratios are such that this movement of the arm 48 results in a half revolution of the head 67 so as to interchange the positions of the mandrels 69.

105 The sizing apparatus is mounted in a pair of brackets 71 and 72. A sleeve 73 is mounted in ball bearings 74 and 75 in the brackets 71 and 72 respectively. This sleeve has keyed thereto a pulley 76 for driving the same and carries at one end a sizing die 77. Mounted in the bracket 72 is a sleeve 78 passing over the sleeve 73 and carrying a ball bearing 79 upon which the pulley 80 is adapted to run, said pulley carrying a short sleeve 81 in which is mounted another sizing die 82. A stationary sleeve 83 is mounted in a bracket 84 and extends through the bore of the sleeve 73 to a point adjacent the dies 77 and 82. The sleeve 83 carries at its extremity

a clutch device 85 of any suitable type adapted to prevent retrograde movement of the tube being operated upon. As seen from Figure 4, the structure is such that the dies 5 77 and 82 are mounted closely adjacent one another. The pulleys 76 and 80 are driven by means of belts 86 and 87 from any suitable source of power not shown. The arrangement of the belts is such, as for instance by crossing the belt 87, that the dies 10 77 and 82 are driven in opposite directions or at relatively different speeds.

Mounted on the bracket 4 and closely adjacent the die 82 is a hood 88. This hood is 15 pivoted at 89 to the bracket 4 and engages a fastening screw 90 for securing the same in place. By loosening the screw 90 the hood may be swung about the pivot 89 so as to clear the mechanism. Mounted on the hood 20 88 and pivoted at 91 and 92 is a pair of arms 93 and 94 respectively. These arms carry beveled blades or abutments 95 arranged to rest upon opposite sides of the tube 7 being operated upon. The arms 93 25 and 94 are held in engagement with the tube by a spring 96. These arms are arranged to move in slots 115 in a cover plate 116 mounted on the hood 88. The inner walls 117 serve as abutments to receive the arms 93 30 and 94 when the mandrel is drawn out from between the blades 95. This keeps the arms from collapsing so as to prevent the entrance of another tube. The blades 95 snap together behind the tube when it has been fed 35 in all the way, so as to prevent retrograde movement of the tube upon withdrawal of the mandrel. The arm 94 has an extension 97 engaging an adjusting screw 98 on the lever 99 pivoted at 100 on the brackets 4 and connecting by a link 101 with a spring-pressed latch bolt 102 arranged in the path of a lever 103 pivoted at 104 on one of the piers 2 and tensioned by a spring 105 anchored to the bed 1. The arm 103 is provided with an 40 extension 106 beyond the pivot 104 and connected to an adjustable link 107 connected to the operating element of the clutch 18. By referring to Figures 1 and 6, it will be seen that should a tube fail by buckling or 45 the like, the abutment 95 will be shifted from the normal position, thereby shifting the arm 99 which, acting through the link 101, withdraws the bolt 102 out of the path of the arm 103 which is thereby released so as to swing to the left, Figure 1. At the 50 same time, the extension 106 moves the link 107 so as to release the clutch 9 and stop the feeding mechanism.

60 Résumé of operations.

The tubes to be operated upon are fed to the tube magazine comprising the channels 5 and 6 and feed downwardly therealong by gravity. As each tube passes the roll 14 it receives a coating of grease therefrom. The

roll 14 is supplied with grease from the barrel 10 in a manner already described. The roll 14 and the conveyor 12 may be mechanically driven by means of gears 108, 109 and 110 driven by a belt wheel 111 from any suitable source of power. Supposing an operation on a tube to be just beginning, the carriage 40 will have been withdrawn to its extreme right hand position, Figures 1 and 2. In this position, the arm 29 will just be beginning its movement to the left, Figure 2, so as to start the feeding operation. This moves the carriage 40 slowly to the left as previously described. Such movement of the carriage enters the tube 7 to be operated upon into the dies 82 and 77. These dies operate successively to size the tube. The dies rotate in opposite directions and are spaced closely adjacent one another so that the twist occasioned by the operation will be confined to a very short section of the tube, whereby the stresses in the tube are reduced to a minimum. At the same time each die holds the tube against rotation by the other die and, therefore, holds the tube 75 for operation thereupon by the other die. As the carriage 40 moves forward, the tube being operated upon is passed through the dies and at the same time the other mandrel is passed or entered into the lowermost tube 80 in the magazine. Upon completion of the sizing operation the carriage will be moved backward on the return stroke. Upon such movement, the clutching device 85, supplemented by the blades 95, will prevent the tube from being withdrawn with the mandrel, while at the same time a lowermost tube 85 in the magazine will be withdrawn therefrom as the mandrel recedes. The head 67 90 is locked against rotation during these operations by the latch 112 controlled by an arm 113. The latch 112 is in the form of a sliding bolt provided with a rack adapted to engage a pinion 119 on a shaft 120 on the end of which the arm 113 is loosely mounted. The arm 113 is provided with an extension 100 121 substantially at right angles therewith. A spring 122 anchored on the housing 68 is connected with the extension 121 so as to maintain the arm 113 yieldingly in its downwardly extending position as shown in Figure 1. An arm 123 is fixed to the shaft 120 adjacent the arm 113. This arm is held by a spring 124 in retracted position so as to maintain the latch 112 in engagement with the head 67. The arm 123 is provided with a pin projecting into the path of the arm 113 so that when said arm moves to the left, Figure 1, it will strike the pin, move the arm 123 to the left, Figure 1, thereby rotating the shaft 120 and the pinion 119 so as to withdraw the latch and release the head 67 for rotation. As the carriage 40 moves backward on the return stroke, a roller on the end of the arm 113 engages 105 110 115 120 125 130

the abutment 114 adjustably mounted adjacent the ways 41. The abutment 114 is adjusted to such a position along the ways 41 so as to engage the arm 113 at the proper 5 moment to latch the head 67 for rotation by the action of the cam rise 70 as previously described. The abutment 114 at both ends is tapered so that the arm 113 can ride completely over it. The cam rise 70 acts to 10 rotate the head 67 during the time that the arm 113 is passing over the flat top of the abutment 114. When the arm 113 passes the abutment 114, the head 67 has already been rotated out of engagement with the latch 112 15 so that said latch will under the action of the spring 124 be brought to bear against the flat rear surface of the head 67 until said head has executed a half revolution when the latch will drop into the second 20 notch so as to lock the head for the next operation. As the next forward stroke commences, the arm 113 again rides over the abutment 114 but is this time deflected to the right, Figure 1, which movement will 25 have no effect on the latch 112. Such a half revolution of the head 67 swings the mandrels 69 so as to bring the one carrying the new tube just extracted from the magazine to the position for operation by the dies 30 and positions the other mandrel so as to be ready to enter the next tube in the magazine. Upon completion of these movements, the next forward stroke is ready to begin and the cycle of operations is repeated. 35 Should failure of the tube or choking of the mechanism occur, the tube being of paper will buckle at the point where it enters the die 82 so that the elements 95 will be actuated to stop the feed as previously described. 40 It will be noted, therefore, that this invention accomplishes its objects. The dies spaced closely adjacent one another and rotating relatively are adapted to relieve the tube of excessive strains and at the same 45 time, each die holds the tube for operation by the other. The greasing of the tubes in the magazine and prior to being inserted in the dies provides smooth operation of the dies and leaves the tubes with a high finish. 50 The machine automatically takes the tubes from the magazine and passes them through the sizing mechanism. Provision is made for abnormal conditions, such as the mechanical failure of the tube, by which is 55 meant breaking, bursting, buckling, collapsing or the like, or the choking of the mechanism so that the operation is stopped if any such abnormal conditions should develop. 60 It is obvious that various changes may be made in details of construction without departing from the spirit of this invention; it is, therefore, to be understood that this 65 invention is not to be limited to the specific details shown and described.

Having thus described the invention, what is claimed is:

1. In the art of sizing tubes, the process comprising, passing the tube through dies arranged in tandem, and rotating the dies relatively in order to cause one die to hold the tube for operation thereon by the other. 70
2. In the art of sizing tubes, the process comprising, passing the tube through dies arranged closely adjacent and in tandem, and rotating the dies relatively in order to cause one die to hold the tube for operation thereon by the other. 75
3. A machine for sizing tubes comprising, a pair of dies arranged in tandem for operation on the tube, and means for rotating said dies relatively, adapted to cause one die to hold the tube for operation thereon by the other. 80
4. A machine for sizing tubes comprising, a pair of dies arranged closely adjacent and in tandem for operation on the tube, and means for rotating said dies relatively, adapted to cause one die to hold the tube for operation thereon by the other. 85
5. A machine for sizing tubes comprising, mechanism for operating on the tube, means for passing the tube through said mechanism, and means continuously engaging the tube for retaining the same against retrograde movement. 90
6. A machine for sizing tubes comprising, mechanism for operating on the tube, a reciprocating element for passing the tube through said mechanism, and means continuously engaging the tube for retaining the same against retrograde movement. 100
7. A machine for sizing tubes comprising, mechanism for operating on the tube, means for passing the tube through said mechanism, and means movable by and acting upon abnormal condition of the tube adapted to stop operation on the tube. 105
8. A machine for sizing tubes comprising, mechanism for operating on the tube, means for passing the tube through said mechanism, and means acting upon mechanical failure of the tube adapted to stop operation on the tube. 110
9. A machine for sizing tubes comprising, mechanism for operating on the tube, means for passing the tube through said mechanism, and an element adjacent the tube adapted upon abnormal condition thereof to effect stopping of the operation thereon. 115
10. A machine for sizing tubes comprising, mechanism for operating on the tube, means for passing the tube through said mechanism, and an element shifted upon mechanical failure of the tube adapted to effect stopping of the operation thereon. 120
11. A machine for sizing tubes comprising, mechanism for operating on the tube, means for passing the tube through said mechanism, and an element shifted by the 125

tube upon abnormal condition thereof adapted to effect stopping of the operation thereon.

- 5 12. A machine for sizing tubes comprising, a tube magazine, mechanism for operating on the tubes, means for taking the tubes from said magazine and for passing them through said mechanism, and means for greasing the tubes while in the magazine.
- 10 13. A machine for sizing tubes comprising, a tube magazine, mechanism for operating on the tubes, means for taking the tubes from said magazine and for passing them through said mechanism, and means cooper-

ating with said magazine for applying 15 grease to the tubes before they are passed through said mechanism.

14. A machine for sizing tubes comprising, mechanism for operating on the tube, means for passing the tube through said 20 mechanism, and greasing mechanism arranged in the path of the tubes in said magazine.

In testimony whereof we affix our signatures this 29th day of January, 1923.

JOHN M. OLIN.

GEORGE W. SCHAUERTE.

HANS ERNST.
